(57) **CLAIM**

The ornamental design for a diagnosis apparatus for laboratories, as shown and described.

DESCRIPTION

FIG. 1 is a front perspective view of a diagnosis apparatus for laboratories, showing our new design;

FIG. 2 is top-front perspective view thereof;

FIG. 3 is top-rear perspective view thereof;

FIG. 4 is a top view thereof;

FIG. 5 is a front view thereof;

FIG. 6 is a rear view thereof;

FIG. 7 is a right side view thereof; and,

FIG. 8 is a left side view thereof.

The broken lines in the drawing views are included for the purposes of illustrating portions of the diagnosis apparatus for laboratories that form no part of the claimed design.
